BOTTLE OR SIMILAR ARTICLE

Robert Adell, 1365 Balmoral, Detroit, Mich.

Filed Aug. 21, 1959, Ser. No. 57,253

Term of patent 14 years

(Cl. D58—7)

Fig. 1 is a perspective view of a bottle embodying my new design;

Fig. 2 is an enlarged fragmentary sectional view taken on the line 2—2 of Fig. 1; and

Fig. 3 is a bottom plan view thereof.

I claim:

The ornamental design for a bottle or similar article, as shown.
